UNITED STATES PATENT OFFICE.

CLARK T. HENDERSON, OF MILWAUKEE, WISCONSIN, ASSIGNOR, BY MESNE ASSIGNMENTS, TO THE CUTLER-HAMMER MFG. CO., OF MILWAUKEE, WISCONSIN, A CORPORATION OF WISCONSIN.

ELECTROMAGNETIC SEPARATOR.

1,245,717.

Specification of Letters Patent.

Patented Nov. 6, 1917.

Application filed June 20, 1914. Serial No. 846,292.

To all whom it may concern:

Be it known that I, CLARK T. HENDERSON, a citizen of the United States, residing at Milwaukee, in the county of Milwaukee and 5 State of Wisconsin, have invented new and useful Improvements in Electromagnetic Separators, of which the following is a full, clear, concise, and exact description, reference being had to the accompanying drawings, forming a part of this specification.

This invention relates to electromagnetic separators.

One of the objects of the invention is to provide improved means for extracting free 15 magnetic particles from flowing substances.

A further object is to provide an improved electro-magnetic separator wherein the material treated flows in a direction parallel to the lines of magnetic flux and where- 20 in the poles of the magnet present a large area for attracting and collecting the magnetic content.

Further objects and advantages will appear hereinafter in connection with the description of the accompanying drawing, which illustrates, partially in section, an embodiment of the invention designed more particularly for removing magnetic particles suspended in fluids, such as slip used 25 in the manufacture of china, pottery and porcelain.

The device comprises, in general, a magnet winding 1 coiled about a tubular sleeve 2 which constitutes a passage for the material treated and which is provided with two or more transversely disposed apertured members magnetized when the winding is energized. The members 3 are spaced along the interior of the sleeve and are provided 30 with numerous openings extending in a direction parallel to the flow of the material treated and to the magnetic lines of force. The faces of members 3 also alternate in polarity so that, in effect, the device includes 40 two or more subsidiary magnets all induced by the large winding 1.

Referring more specifically to the drawing, the same shows the winding 1 wound on a central sleeve 2 of non-magnetic material and inclosed in a magnetic iron frame 4. The frame 4 comprises similar sections bolted together and located axially of the

sleeve 2 by exterior flanges on the latter. The ends of the sleeve are preferably extended beyond the ends of the winding and 55 are provided with threaded reducing bushings 5 which enable the device to be connected in a pipe line. The apertured members 3 span the sleeve 2 and are supported therein between alternate magnetic rings 6 60 and non-magnetic rings 7. The rings 6, 7 and the members 3 are retained within the sleeve between a shoulder 8 at one end of the latter and a threaded tap 9 at the other. The apertured members 3 preferably comprise 65 relatively coarse wire screens or perforated metal plates. It is to be understood, however, that other forms of magnetic members may be employed, if desired.

The device is designed to be installed in 70 upright position and connected with the fluid supply so that the latter enters the lower end of the sleeve 2 and emerges from the device at its upper end. In this manner the flow of the liquid is substantially uniform at all points within the sleeve, and contact of the material with some exposed portion of the screens or plates 3 is practically insured. When the winding 1 is energized the screens are strongly magnetized 75 80 and attract the free magnetic particles in the material and thus separate the same from the remainder of the flowing mass.

In operation, the material may be passed through the device until the accumulation 85 of the magnetic particles on the attracting screens or plates clogs the apertures in the latter to a degree which impedes further passage of the material. The device may be readily cleaned, either by depriving the 90 winding 1 of current and connecting the lower bushing 5 to a waste pipe, and then flushing the sleeve by pouring water into the upper end thereof, or by removing the tap 9 and then taking out the screens and 95 cleaning the same while removed.

What I claim as new and desire to secure by Letters Patent is:

1. In an electromagnetic separator, in combination, an electromagnetic winding, a 100 non-magnetic tubular member extending therethrough, a series of perforated magnetic members transversely spanning said tubular member and means for removably

- securing said perforated members within said tubular member and for spacing the same within the field of said winding.
2. In an electromagnetic separator, in combination, a magnetic winding, a magnetic frame therefor, a non-magnetic tubular member extending through said winding and said frame and constituting a passageway for the flowing material to be treated, a series of magnetic screens transversely spanning said tubular member and disposed within the field of said winding, and means for removably securing said screens within said tubular member and for spacing the same within the field of said winding.
3. In an electromagnetic separator, in combination, an electromagnetic winding, a non-magnetic tubular member extending therethrough, a series of perforated magnetic members transversely spanning said tubular member and disposed within the field of said winding, a series of rings arranged within said tubular member for spacing said perforated members and means for removably securing said rings and said perforated members within said tubular member.
4. In an electromagnetic separator, in combination, an electromagnetic winding, a non-magnetic tubular member extending therethrough, a plurality of magnetic and non-magnetic rings alternately arranged within said tubular member, a plurality of perforated magnetic members spanning said tubular member and separated by said rings and means for removably securing said rings and said perforated members within said tubular member.
5. In an electromagnetic separator, in combination, a magnetic winding, a magnetic frame surrounding said winding, a non-magnetic tubular member extending through said winding, means for connecting the ends of said tubular member in a pipe line and a series of perforated magnetic members transversely spanning said tubular member and disposed in a spaced relation within the field of said winding.
6. In an electromagnetic separator, in combination, a magnet winding, a magnetic frame therefor, a non-magnetic sleeve extending through said winding and frame, a plurality of magnetic and non-magnetic rings alternately arranged within said

sleeve, and a plurality of magnetic members spanning said sleeve and separated by said rings.

7. In an electromagnetic separator, in combination, a magnet winding, a magnet frame therefor, a shouldered non-magnetic sleeve extending through said winding and frame, a plurality of magnetic and non-magnetic rings alternately arranged within said sleeve, a plurality of perforated magnetic members spanning said sleeve and separated by said rings, and removable means for clamping said rings and members axially against the shoulder of said sleeve.

8. In an electromagnetic separator, in combination, a non-magnetic tubular member, a magnetic winding surrounding the same, a magnetic frame surrounding said tubular member and said winding, said tubular member having its ends projecting beyond said winding and said frame to provide portions for connecting the same in a pipe line and said frame comprising similar cylindrical sections separately removable axially of said tubular member and independently of said winding.

9. In an electromagnetic separator, in combination, a tubular member, a magnetic winding surrounding said member, a magnetic frame surrounding said tube and winding, said frame comprising similar cylindrical sections separately removable axially of said tube and independently of said winding, and means for determining the axial position of said frame and winding with respect to said member.

10. In an electromagnetic separator, in combination, a tubular member, a magnetic winding surrounding said member, a magnetic frame surrounding said tube and winding, said frame comprising similar cylindrical sections separately removable axially of said tube and independently of said winding, and exterior flanges on said member for determining the axial relation of said frame and winding thereto.

In witness whereof, I have hereunto subscribed my name in the presence of two witnesses.

CLARK T. HENDERSON.
